Fig. 3

Fig. 4

Fig. 5

Fig. 6

FIG. 1 is a right side elevation view of a toy locomotive, showing my new design;

FIG. 2 is a left side elevation view of the same;

FIG. 3 is a top plan view of the same;

FIG. 4 is a bottom plan view of the same;

FIG. 5 is a front elevation view of the same;

FIG. 6 is a rear elevation view of the same.

I claim:

The ornamental design for a toy locomotive, substantially as shown.
